UNITED STATES PATENT OFFICE.

CHARLES ADLER, JR., OF BALTIMORE, MARYLAND.

ROADWAY-CROSSING SIGNAL.

1,394,264.

Specification of Letters Patent.

Patented Oct. 18, 1921.

Application filed February 14, 1920. Serial No. 358,769.

To all whom it may concern:

Be it known that I, CHARLES ADLER, Jr., a citizen of the United States, residing at Baltimore, in the State of Maryland, have 5 invented certain new and useful Improvements in Roadway-Crossing Signals, of which the following is a specification.

My invention relates to an improved crossing signal for roadways that cross over rail- 10 way tracks.

The object of the invention is to provide an extremely simple signal device that will be set into operation by an approaching train or vehicle on the tracks and which will be 15 cut out of operation immediately upon the front wheels of the foremost car, engine or vehicle passing the crossing.

A further object of the invention is to combine an audible and a visual signal in 20 the same circuit,—the audible signal being located at the crossing where it can be heard by persons about to make the crossing, and the visual signal preferably placed to the side of the crossing and along the trackway 25 whereby the same may be seen by the engineer or motorman of the vehicle who will be able to see, by the position of the visual signal whether the signal circuit for the crossing ahead is operating or not.

30 The invention is diagrammatically illustrated in the accompanying drawing wherein the numerals 1 and 2 designate the two track-rails, and 3, indicates the roadway crossing the said track-rails which is to be 35 protected by an audible signal such as a bell.

In carrying out the invention I provide 40 insulation 4, in the two track-rails both at the crossing and at each side thereof whereby to form two insulated track blocks or 45 sections 5 and 6 respectively,—one at each side of the road crossing 3.

For the block or section 5, I provide a relay 7, and for the block or section 6, there is provided another relay 8.

45 The relay 7, has a connection 9, with one side of a current-supply 10, provided from any suitable source, and said relay 7, has another connection 11, that leads to the track-rail 1, of section or block 5.

50 A connection 12, is provided from the other side of the said current-supply 10, to the track-rail 2, of said section or block 5, so that the only break in the circuit from the current-supply 10, through the relay 7 55 and the two track-rails is the break between

the track-rails 1 and 2 in said section or block 5. The circuit is therefore a normally open circuit and the relay 7 is normally de-energized.

In a similar manner the relay 8, for the 60 block or section 6, has a connection 13, with one side of another current-supply 14 and another connection 15, leads from said relay 8 and connects with the track-rail 1, of the block or section 6. 65

From the other side of current-supply 14, I provide a connection 16, that leads to the track-rail 2, of said section or block 6.

The relay 7, is provided with an armature 17, which is pivoted at 18, to a suitable support 19, and this armature carries a front contact 20, at one end and a back contact 21, at the opposite end. Some means, such as light spring 22, is provided to normally pull the back contact-end of the armature 75 down when the relay 7, is de-energized as it is illustrated in the drawing.

A mercury contact device 23, is provided at the rear end of the armature so that when the latter is down its back contact 21, will 80 dip into the mercury.

The relay 8 is also provided with an armature 24, which is pivoted at 25 to a support 26 and this armature also carries a front contact 27 and a back contact 28. A 85 light spring 29, is also employed to tend to draw the back contact-end of this armature down when the relay 8 is de-energized.

A mercury contact device 30, is provided for the rear contact 28, of armature 24, for 90 a purpose presently to be explained.

Between the two relays 7 and 8, I show a single mercury contact device 31, which is so located that either of the front contacts 20 or 27, may close a circuit therethrough as 95 will presently be explained.

A loop or wire connection 32, is provided from the pivot-point 18, of armature 17, to the pivot-point 25, of armature 24, and this loop is maintained at all times between the 100 two armatures.

A second loop or wire connection 33, is always maintained between the mercury contacts 23 and 30.

My device also makes use of a third connection with a current supply 34, an alarm device such as a bell 35, and a semaphore or paddle arm 36. This arm may be mounted on a support carrying a lamp so that the position of the paddle, at night, may be seen 110

by the light displayed. This is a detail and not essential to the invention.

The alarm device is located at the roadway crossing 3, while the paddle 36, is preferably located some distance back on the trackway where it can be seen by the engineer before the crossing is reached.

The provision of this paddle is desirable because the noise of the engine may drown 10 the sound of the alarm as the latter is passed and the engineer would not know whether or not the alarm is sounding.

Between the current supply 34, the signals 35 and 36 and the central mercury contact 31, I provide what may be termed the signal circuit, whereas the circuits involving 15 the current-supplies 10 and 14, the relays 7 and 8, and the track-rails 1 and 2, may be termed the control circuits.

20 The signal circuit includes a connection 37, from one side of the current-supply 34, to the loop 33, that connects the mercury-contacts 23 and 30.

From the other side of the said signal current-supply 34, I provide a connection 38, to the bell 35; a connection 39, from the bell to the paddle-operating means to the central mercury-contact device 31.

By reference to the drawing it will be 30 noted that the armatures 17 and 24 are of such length that in case both front ends are down, said ends will lap. The object of this construction will presently be explained.

In the operation of my device two sets of 35 circuits are employed,—one being the relay circuit which is controlled through the track-rails, and the other the signal circuit which is controlled through the front-point of one armature and the back point of the 40 other armature. The signal circuit is closed, only when the two armatures 17 and 24 are in reverse positions, that is, one up and the other down. When both armatures are up or both down the signal circuit will be interrupted.

The operation is as follows:

Let 41, designate a vehicle or train traveling on the tracks 1 and 2, in the direction of the dart. When the vehicle entered the 50 block or section 6, its wheels and axles closed the relay circuit from current-supply 14, across the tracks 1 and 2 to and through relay 8, thereby energizing said relay 8 and drawing armature 24, down until its front contact 27, makes contact with the mercury in the central mercury contact device 31. Immediately upon making this contact a signal circuit was established as follows:

From signal current-supply 34, by wires 60 37 and 33, through the mercury contact 23, to front point 21, of armature 17; then by loop-wire 32, to the armature 24, which was drawn down when relay 8, was energized; through said armature 24, to the front point 65 27; then through mercury-contact 31, to

wire 40, paddle-mechanism 36, wire 39, bell 35, and wire 38 back to the current-supply 34.

It will thus be noted that this signal circuit is established through the down front 70 point 27 of attracted armature 24, and the down back-point 21, of the released armature 17.

Under the conditions just explained and as illustrated in the drawing the signal circuit is completed and the signals are operating, and will continue to operate until the vehicle 41, crosses the insulation 4, between blocks or sections 5 and 6.

Immediately upon the front wheels of the 80 vehicle 41, passing into section 5, the circuit from current-supply 10 through the tracks of said section 5, and through relay 7, will be established thereby energizing said relay 7, and attracting armature 17.

The latter armature 17, will be drawn down so that its front end will overlap the front end of the armature 24, because armature 24, will be held down by relay 8, until the vehicle or the entire train passes out of 90 section 6.

By placing the insulation 4, at the road crossing 3, I am able to cut out the operation of the bell 35, as soon as the road crossing is blocked by the vehicle or train and the 95 signal is no longer needed.

At this moment in the operation of the device, both armatures 17 and 24, will be down and both of the back contacts 21 and 28 will be up and therefore out of contact 100 with mercury-contacts 23 and 30.

With both of these back contacts interrupted or open, current from the signal current-supply 34, cannot pass to the signal mechanism and the latter will at once 105 become inoperative.

When the vehicle or train 41, has passed entirely out of section or block 6, the circuit through the relay 8, will be broken, but as armature 17 is held down by the energized 110 relay 7, and the front end of that armature 17 overlaps the front end of the armature 24, the latter cannot swing up and both armatures will therefore be kept down until relay 7 becomes deenergized. The signal 115 therefore remains cut-out and inoperative.

When the vehicle passes out of section or block 5, the relay 7, will become deenergized because of the interruption of the relay circuit between the two track-rails 1 and 2 of 120 said block 5, and upon deenergizing this relay 7, its armature 17, will move up and by so doing will release the front end of armature 24, which latter will also swing up and all circuits will be broken.

Having described my invention, I claim,—

1. In a signal device for railway crossings the combination with the track-rails formed into separated insulated sections at opposite sides of a crossing-point, a relay for one sec- 130

tion said relay having a connection with a current-supply and another connection with one of the track-rails; another connection from said current-supply to the other track-
5 rail of said section; a relay for the other insulated track-section and said latter relay having connection with a current supply and the two rails of said other track-section; an armature for each relay and
10 each armature having a front contact-point and a back contact-point said armatures being arranged so that when both are down one will engage and hold the other; a signal device, and a signal circuit including the
15 front point of one armature, the back point of the other armature and the signal device when the armatures are in reverse positions.

2. In a signal device for railway crossings the combination with the track-rails formed
20 into separate insulated sections at opposite

sides of a crossing-point, a relay for each section; a separate track-controlled circuit for each relay; an armature for each relay and each armature having a front contact and a back contact; said armatures being 25 arranged so that when both are down one will engage and hold the other; a connection between the two armatures whereby the front-point of one armature may be placed in circuit with the back-point of the 30 other when the armatures are in reverse positions; a signal device and a signal circuit including the signal device, the connection between the two armatures, the front-point of one armature and the back-point of the 35 other armature when one relay only is energized.

In testimony whereof I affix my signature.

CHARLES ADLER, JR.
